CLAIM

I claim the ornamental design for the utensil holder, as shown and described.

DESCRIPTION

FIG. 1 is a front-facing perspective view of the utensil holder according to the invention;

FIG. 2 is a rear-facing perspective view of the utensil holder of FIG. 1;

FIG. 3 is a front view of the utensil holder of FIG. 1;

FIG. 4 is a back view of the utensil holder of FIG. 1;

FIG. 5 is a side view of the utensil holder of FIG. 1;

FIG. 6 is a side view of the utensil holder of FIG. 1;

FIG. 7 is a bottom view of the utensil holder of FIG. 1; and,

FIG. 8 is a top view of the utensil holder of FIG. 1.
